UNITED STATES PATENT OFFICE.

GEORGE L. BRISBIN, OF PUNXSUTAWNEY, PENNSYLVANIA.

COLLAR-FASTENING DEVICE.

Application filed November 6, 1922. Serial No. 599,314.

To all whom it may concern:

Be it known that I, GEORGE L. BRISBIN, a citizen of the United States, and a resident of Punxsutawney, in the county of Jefferson 5 and State of Pennsylvania, have invented a new and Improved Collar-Fastening Device, of which the following is a full, clear, and exact description.

This invention has relation to fastening devices and has particular reference to a device for associating a collar with the rear portion of the neckband of a shirt.

The invention contemplates a collar fastener which operates to effectively attach the collar to the usual guard pocket at the rear of the shirt neckband; which greatly facilitates the application and removal of the collar from the shirt; which permits the tie to readily slide between the folds of the collar; which lies flat, thereby eliminating the raised portion or hump which causes a soiled spot by the contact of the vest or coat collar therewith, and at the same time renders the same more comfortable to the 20 wearer.

The invention further contemplates a device of the character described, which is extremely simple in its construction and which is inexpensive to manufacture and produce.

With the above recited and other objects in view, the invention resides in the novel construction set forth in the following specification, particularly pointed out in the appended claims and illustrated in the accompanying drawing, it being understood that the right is reserved to embodiments other than those actually illustrated herein to the full extent indicated by the general meaning of the terms in which the claims are expressed.

In the drawing—

Figure 1 is a fragmentary inside view of the rear portion of the collar with the fastening device in applied position.

Fig. 2 is a vertical sectional view therethrough taken approximately on the line 2—2 of Fig. 1 and illustrating the application of the collar to the shirt by means of the improved fastener.

Fig. 3 is a fragmentary sectional view taken approximately on the line 3—3 of Fig. 2.

Fig. 4 is a detail perspective view of the fastener removed.

Referring to the drawing by characters of reference, A and B designate respectively

the inner and outer folds of a collar, the former being provided with the usual rear buttonhole C. D designates a shirt having a neckband E which is provided with the 60 usual rear guard pocket F.

The fastener constituting the invention consists of a substantially inverted V-shaped hook 10 including divergent arms 11 connected together at their upper ends by a 65 bight 12. The lower ends of the arms 11 are provided with upwardly bent and laterally inclined portions 13, the terminals of which are curved inwardly as at 14 and thence downwardly as at 15 to provide parallel end 70 legs 15. The juncture of the terminals 14 with the portions 13 produces a shoulder 16. The fastening device is preferably constructed from a single length of wire bent into the shape heretofore set forth. In practice the bight 12 of the hook 10 is first inserted through the buttonhole from the outer side of the inner fold until the lower extremities of the legs are disposed in the same plane with the buttonhole. The lower 75 extremities are then forced through the buttonhole and the laterally inclined portions 13 are then forced downwardly to lie inside of the inner fold A of the collar. The shoulders or projections 16 snap through or 80 just below the buttonhole C due to the inherent resiliency of the material from which the fastener is formed. This leaves the remaining parallel depending end legs 15 and a portion of the curved terminals 14 at the 85 outer side of the inner fold. The tie G is designed to lie above the fasteners of the double fold type as illustrated, but in the straight or wing type collar which have but a single fold the terminal legs 15 may be 90 employed to receive the tie therebeneath for 95 preventing the riding of the same upwardly.

After the fastener has been applied to the collar, the hook 10 is inserted within the usual guard pocket F at the rear of the shirt 100 neckband, thus greatly facilitating the application of the collar to the neckband and the removal of the same therefrom. In view of the fact that the fastener lies very flat the raised portion or hump usually caused by a 105 collar button is eliminated, thus avoiding the soiled spot caused by contact of the vest or coat collar with the outer fold collar and tending toward comfort to the wearer.

I claim:

1. As a new article of manufacture, a collar fastening device consisting of a length

of resilient wire bent medially to provide a hook, consisting of downwardly diverging legs connected by a bight at their upper ends, and an attaching portion at the lower extremity of each leg consisting of an upwardly turned and outwardly inclined limb, an inwardly and outwardly curved portion and a downturned terminal leg, all the parts being arranged in spaced relation to each other with the hook foremost and the terminal legs at the rear.

2. As a new article of manufacture, a collar fastening device consisting of a length

of resilient wire bent medially to provide a hook, consisting of downwardly diverging legs connected by a bight at their upper ends, and an attaching portion at the lower extremity of each leg consisting of an upwardly turned and outwardly inclined limb, an inwardly and outwardly curved portion and a downturned terminal leg, the juncture of said inwardly curved portions with the upwardly inclined limb forming shoulders, as and for the purpose specified.

GEORGE L. BRISBIN.
